A. F. MARSH

SLIDING DOOR AND MOUNTING

Filed Dec. 30, 1922

Patented Aug. 3, 1926.

1,594,543

UNITED STATES PATENT OFFICE.

ANDREW F. MARSH, OF PLAINFIELD, NEW JERSEY.

SLIDING DOOR AND MOUNTING.

Application filed December 30, 1922. Serial No. 609,811.

The present invention relates to building construction, having reference particularly to an improved sliding door adapted for closing a wide doorway of the end of a relatively narrow building, as a garage.

The invention has for its principal object the provision of a strong and durable sliding door and novel means for hanging the same, whereby it may be alternatively maintained in closed position across a doorway and in open position at right angles to and closely adjacent to one side of said doorway, thus permitting the door to be operated when the major part of the building floor space is occupied by vehicles.

In carrying out my invention, I provide a sectional sliding door, hangers rotatably mounted on the door sections and having roller bearings, an upper rail for supporting said hangers, a lower guide rail, and hooks mounted on the door sections for engaging said guide rail, all as hereinafter fully described and specifically set forth in the appended claims.

In the accompanying drawings forming part of this specification, Figure 1 is an end elevation of a garage, shown partly in section, and having my improvements attached;

Fig. 2 is a vertical sectional view taken on the line 2—2 of Fig. 1;

Fig. 3 is a sectional plan view taken on the line 3—3 of Fig. 1;

Fig. 4 is a sectional plan view drawn on an enlarged scale and taken on the line 4—4 of Fig. 2; and

Fig. 5 is a fragmentary face view shown partly in section.

In the drawings, 1 indicates the garage structure in general, and 2 the doorway located across the major part of one end thereof.

Mounted interiorly above the doorway and spaced from the end wall 3 and one side wall 4 of the building, by means of beams 5 and 5^a, is an L-shaped metal rail consisting of branches 6 and 7 connected at their point of intersection by an integral curved part 8.

The door consists of two sections, 9 and 10 adapted to be locked together at their abutting edges by means of any suitable lock, as 11.

The door sections, at their respective upper corners, are recessed for the reception of metal tubes 12, which are respectively held

in place by means of a U-shaped metal strap 13, which is fixed to the door by means of suitable bolts or screws 14.

Rotatably fixed within each tube element 12 is a wrought metal hanger comprising a body 15 having an integral loop-member 15^a, in which is mounted a roller bearing 16, and a lower member 17 twisted at an angle of forty-five degrees to the transverse plane of the body 15 and having a slot 18, which engages a transverse bolt 19, whereby the hanger is held against sliding movement but permitted turnable movement within the tube 12, bearing pins 20 are secured to and project from the members 17 to prevent swinging movement of the hanger in relation to the tube 12 by the contact of these pins with the tube wall.

Each door section is provided on one edge adjacent its lower end with a countersunk plate 21 having an angularly directed hook 22 for engaging a guide rail 23, whereby the door sections are held against swinging movement while they are being shifted. A bearing member 24, having a depression 24^a, over which vehicle wheels may pass, is also provided to hold the door sections against the door frame 1^a and prevent swinging movement when they are closed, and a stop 25 is provided to limit the movement of the door section 9, when it is being closed; a similar stop 26 being provided to limit the movement of the door section 10 when the door sections are shifted on the rail branch 7 to open the doorway.

While I have illustrated and described a fair example of my improvements, I do not wish to be understood as confining myself to the specific details of construction shown, as under the spirit of my invention I believe that I am entitled to employ such variations of minor detail as may fall within the scope of the appended claims.

In the operation and use of my invention, it is manifest that when the door sections are placed for closing the doorway and locked together, as shown in full lines, Fig. 3 of the drawings, they are securely held against slidale movement because of their combined width, but when unlocked, owing to their relative narrow widths, they may be readily moved and shifted from the rail branch 6 to the rail branch 7, as shown by dotted lines Fig. 3, whereupon a vehicle may be readily introduced through the doorway and placed

to occupy the major part of the floor space of the garage without interfering with the door closing operation.

Having thus described my invention, what I claim as new and desire to secure by Letters Patent, is:—

1. In a sliding door mounting, a socket tube, means for retaining said socket within a recess in said door; a roller hanger provided with a shank having a slot therethrough, and a bolt passing through said tube and said shank slot to retain said shank in said tube while allowing limited motion therebetween upon a common axis.
2. In a sliding door, a door panel provided with a recess at its upper corner, a tubular hanger mounting in said recess, a retainer strap surrounding three sides of said recess and engaging the surface of said

panel therebeyond, roller hangers provided with shanks having a slot therethrough, and a single bolt passing through said tubular mounting, said retainer strap and said shank slots to retain the whole in assembly.

3. In a sliding door hanger, a body portion mounting a roller, a lower member at substantially 45° to said body portion, means engaging said lower member and a retainer, said retainer engaging said door, the said 45° twist between said body portion and said lower member permitting movement of said roller relative to said door at angles greater than 90° to the plane thereof to permit negotiation of curved hanger tracks.

Signed at Plainfield, in the county of Union and State of New Jersey this 28th day of October A. D. 1922.

ANDREW F. MARSH.
